(57) **CLAIM**

The ornamental design for a combined cosmetic jar and cap, as shown and described.

DESCRIPTION

FIG. 1 is a top perspective view of a combined cosmetic jar and cap showing the claimed design;

FIG. 2 is a bottom rear perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is an exploded view of the combined cosmetic jar and cap shown in FIG. 1;

FIG. 10 is a top front perspective view of the cap, shown separately to show aspects of the design that are not visible when combined;

FIG. 11 is a bottom rear perspective view of the cap;

FIG. 12 is a front view of the cap;

FIG. 13 is a rear view of the cap;

FIG. 14 is a left view of the cap;

FIG. 15 is a right view of the cap;

FIG. 16 is a top view of the cap;

FIG. 17 is a bottom view of the cap;

FIG. 18 is a front perspective view of the jar, shown separately to show aspects of the design that are not visible when combined;

FIG. 19 is a bottom rear perspective view of the jar;

FIG. 20 is a front view of the jar;

FIG. 21 is a rear view of the jar;

FIG. 22 is a left view of the jar;

FIG. 23 is a right view of the jar;

FIG. 24 is a top view of the jar; and,

FIG. 25 is a bottom view of the jar.

(Continued)

The broken lines in the drawings depict portions of the combined cosmetic jar and cap that form no part of the claimed design.
